ATTORNEYS.

UNITED STATES PATENT OFFICE.

HENRY W. BEIL, OF SAN FRANCISCO, CALIFORNIA.

TOOTHBRUSH.

Application filed April 24, 1923. Serial No. 634,310.

To all whom it may concern:

Be it known that I, HENRY W. BEIL, a citizen of the United States, and a resident of San Francisco, county of San Francisco, State of California, have invented a new and useful Toothbrush, of which the following is a specification.

The present invention relates to improvements in tooth brushes, and its particular object is to provide a sanitary tooth brush that will allow the teeth to be flushed at the same time they are brushed. It is proposed to allow water from any suitable source to enter through the handle into the bristle covered area while the brush is being used, and to furthermore distribute the liquid over the entire area, while at the same time guiding the liquid which may be under pressure so as to be directed against the teeth.

The preferred form of my invention is illustrated in the accompanying drawing, in which Figure 1 shows my tooth brush in longitudinal section, Figure 2 in plan view and Figure 3 in cross section taken along line III—III of Figure 1. While I have shown only the preferred form of my invention, I wish to have it understood that various changes or modifications may be made within the scope of the claim hereto attached without departing from the spirit of the invention.

My tooth brush (1) comprises a handle (2) and a plurality of bristles (3) extending laterally from one end of the handle. The bristles are preferably arranged in the manner shown in Figure 2, that is in three parallel rows with each second set of bristles omitted in the central row so as to leave space for perforations (4) which allows each perforation to be surrounded by eight sets of bristles. The central space between the eight sets of bristles is raised to provide

a boss (6) through which the perforation extends, the boss serving as a guide and being adapted to give direction to the stream of liquid forced through a long passage (7) in the handle. The latter passage extends from the bristle covered area to the other end of the handle and communicates with a tube (8) adapted to be secured to the corrugated end of the handle as shown at (9) and to engage with its free end a pipe (11) which may communicate with any suitable supply of water. It may represent for the purposes of this invention the lower end of a faucet connected with the city water supply.

The manner of using the tooth brush will be readily understood from the foregoing description. After the tooth paste has been applied to the brush and the tooth brush has been properly connected to the supply of water by means of the tube (8) the operator may apply the brush to his teeth and while he is brushing the teeth he may turn on the water so that his teeth are flushed while they are being brushed. The particular arrangement of the bosses in the central row of bristles causes a thorough distribution of the water while at the same time giving directional force to the same whereby a thorough cleaning of the teeth is facilitated.

I claim:

A tooth brush comprising an elongated rigid handle with a longitudinal hole having an outlet at the end of the handle adapted for a hose connection, a row of spaced ports extending from the hole through one side of the handle and each surrounded by a raised boss formed integral with the handle, a plurality of spaced tufts of bristles projecting from the handle arranged along all sides of the bosses and between the bosses.

HENRY W. BEIL.
